W. H. CATER,
MEANS FOR PROTECTING DRILLING ROPES AGAINST WEAR.
APPLICATION FILED MAR. 15, 1916.

UNITED STATES PATENT OFFICE.

WILLIAM H. CATER, OF CHICAGO, ILLINOIS.

MEANS FOR PROTECTING DRILLING-ROPE AGAINST WEAR.

1,189,428.

Specification of Letters Patent. Patented July 4, 1916.

Application filed March 15, 1916. Serial No. 84,368.

To all whom it may concern:

Be it known that I, WILLIAM H. CATER, a citizen of the United States, and a resident of Chicago, in the county of Cook and State 5 of Illinois, have invented certain new and useful Improvements in Means for Protecting Drilling-Ropes Against Wear, of which the following is a specification, reference being had to the accompanying drawing.

10 This invention relates to means for protecting a rope against wear when used in drilling a well or under similar conditions. When a rope is drawn up and down in a well and alternately tightened and slackened 15 as is common and well-known practice in connection with drilling machines employing a walking-beam for alternately raising and dropping a line of drilling tools, the rope becomes worn very quickly at that portion of its length being slackened within an 20 uncased bore through sandstone. It is doubtless true that contact of the rope with other portions of the bore or shaft also causes wear upon the rope, but the wear produced by the sandstone is very rapid compared to that produced by any other portion.

It is the principal object of my invention to provide the drilling rope of a well sinking rig of this type with means by which the 25 portion of the rope being reciprocated and alternately tightened and slackened in the sandstone portion of the bore may be protected against undue wear, such protecting means being preferably removable or otherwise adjustable so as to be capable of being 30 shifted upward along the rope as the line of drilling tools passes through and beyond the stratum of sandstone.

It is another object of my invention to 35 provide efficient and serviceable protecting devices of a type especially adapted for the use for which they are designed, and to provide other improvements hereinafter specifically set forth.

40 The preferred means by which I have accomplished my several objects are illustrated in the drawings and are hereinafter specifically described. That which I believe to be new and desire to cover by this application 45 is set forth in the claims.

In the drawings: Figure 1 is a diagrammatic view illustrating a well-sinking rig embodying my improvements; Fig. 2 is a view showing a portion of the bore of a well 50 and illustrating in dotted lines the manner in which my protecting means is serviceable

for attaining the desired end; Fig. 3 is a view showing a section of rope with one of my protecting devices secured thereon by being bent about the rope and pressed 60 tightly into contact therewith; Fig. 4 is a view of the inside face of my protecting device before its application to a rope; Fig. 5 is an end view of the part shown in Fig. 4; Fig. 6 is a view of a modified form of protecting device before its application to a 65 rope; Fig. 7 is a view showing a section of rope with the device of Fig. 6 secured thereon; Fig. 8 is a view of still another form of protecting device; and Fig. 9 is a 70 view showing a short length of rope with the device of Fig. 8 secured thereon.

Referring to Figs. 1 to 5, in which corresponding parts are indicated by the same reference characters,—15 indicates a derrick 75 of any suitable type mounted at the upper end of a well 16. Pivotally mounted upon the derrick 15 at one side thereof is a walking-beam 17 adapted to be reciprocated by a crank 18 connected thereto by means of a 80 link 19. The crank 18 is adapted to be driven from any suitable source of power. The operative end of the walking-beam 17 is adapted to be adjustably connected by any suitable means with a cable 20 extending 85 down into the well, carrying at its lower end a line of drilling tools 21 of any suitable type. The cable 20 is preferably in the form of a wire rope. The cable extends, from the point of its connection with the walking-beam, upward over a sheave 22 at the upper 90 end of the derrick 15 and thence downward about a reel 23 of any suitable type mounted upon the derrick.

As is well understood, the crank 18 is 95 designed to be rotated at such a rate as to give the operative end of the walking-beam 17 a downward stroke in approximately the time required for the line of drilling tools to drop the distance through which the end 100 of the beam is moved. In this movement during the greater portion of the downward stroke the operative end of the walking-beam moves in advance of the drilling tools whereby such tools are permitted to drop 105 for striking a sharp blow at the bottom of the bore. The upward movement of the operative end of the beam is designed to be timed to catch the line of boring tools and to start their upward movement before they 110 are permitted to strike a second time following the rebound of the tools. When the

walking-beam is given its rapid downward movement in excess of the speed at which the drilling tools descend, the cable 20 is slackened momentarily, permitting the rope 5 to be brought into contact with the walls of the bore, as illustrated by dotted lines in Fig. 2. When the rope is thus brought into contact with the walls of the portion of the bore through a stratum of sandstone, the 10 strands of the rope are worn very rapidly, making necessary very soon the provision of a new cable for operating the drilling tools. In order to prevent this rapid wear upon the cable 20 when the cable is being 15 alternately tightened and slackened in a sandstone bore, I have provided the cable 20 with a plurality of protecting devices 24 at intervals along that portion of the cable extending through the sandstone. As the 20 boring proceeds, the lowermost one of the plurality of protecting devices is preferably removed from the cable and replaced in position above the remaining protecting devices, this expedient serving to protect the 25 constantly changing portion of the rope alternately tightened and slackened in the sandstone portion of the bore without the use of an undue number of protecting devices. Whenever any portion of the rope 30 shows undue wear, one or more protecting devices are applied to that portion of the rope without regard to its position relative to a stratum of sandstone. The protecting devices are adapted to be secured in position 35 upon the rope in any suitable manner, either so as to be removable therefrom and thus be adjustable along the rope, or so as to be permanently secured in position upon the rope if desired. It will be understood that the protecting devices are to be 40 of such a size and shape as to permit the cable to be wound upon the drum 23 for the removal of the drilling tools from the bore whenever desired. The distance between the protecting devices along the cable 45 will depend more or less upon the diameter

of the bore and the thickness of the stratum of sandstone. In any event a sufficient number of protecting devices are to be used to afford the desired protection. I have 50 found in actual use that the distance to be maintained between the protecting devices along the cable varies from five to twenty feet under varying conditions.

The form of protecting device 24 illustrated in detail in Figs. 3, 4 and 5 comprises a strip of metal, the strip of metal having ribs or corrugations 25 on its inner face shaped to conform to the face of the cable 20 when the strip is bent about the cable as 60 shown in Fig. 3, the strip being thus capable of gripping the cable very tightly and being held against slippage longitudinally of the cable.

Figs. 6 and 7 show a modified form of 65 protecting device 26 which comprises a thin strip of metal adapted to be wound about the cable 20^a for affording the desired protection.

In Figs. 8 and 9 the protecting device 27 70 comprises a strip of metal adapted to be wound about the cable 20^b so as to have a diagonally-extending butt-joint, as best shown in Fig. 9.

What I claim as my invention and desire 75 to secure by Letters Patent, is—

1. A device for protecting a cable comprising a strip of metal bent to embrace the cable and tightened firmly thereon whereby it is held against movement longitudinally of the cable.

2. A device for protecting a cable comprising a band of metal removably secured about the cable in fixed position thereon.

3. A device for protecting a cable comprising a strip of metal bent to embrace the cable and tightened firmly thereon, the inner face of the strip being ribbed to conform to the shape of the cable whereby the band is held against movement longitudinally of the cable.

WILLIAM H. CATER.
